UNITED STATES PATENT OFFICE.

JOHN H. STEWART, OF WATERLOO, IOWA, ASSIGNOR TO THE ALBRIGHT NELL CO., OF CHICAGO, ILLINOIS, A CORPORATION OF ILLINOIS.

BRISTLE-REMOVING MACHINE.

1,204,518.

Specification of Letters Patent.

Patented Nov. 14, 1916.

Application filed October 24, 1911. Serial No. 656,508.

To all whom it may concern:

Be it known that I, JOHN H. STEWART, a citizen of the United States of America, and a resident of Waterloo, Blackhawk county, 5 Iowa, have invented certain new and useful Improvements in Bristle-Removing Machines, of which the following is a specification.

My invention relates to improvements in 10 bristle-removing machines, and the object of my improvements is to furnish apparatus of simple and effective construction adapted to cleanly remove the bristles from the bodies of hogs after scalding. This object I have 15 accomplished by the means which are hereinafter described and claimed, and which are illustrated in the accompanying drawings, in which:

Figure 1 is a side elevation of my 20 proved machine for removing bristles, with parts broken away to better disclose the construction. Fig. 2 is an upper plan view of said device, and Fig. 3 is a perspective view of a portion of one of the shafts with the 25 scraper-arms secured about it.

Similar numerals of reference designate corresponding parts throughout the several views.

Within a scalding-tank 22 is placed at 30 each side the sprocket-wheels 24 on a transverse rotary shaft 23 located near the bottom of the tank. Similar sprocket-wheels 28' are located on a transverse rotary shaft 27 without the tank above and beyond its 35 right-hand upper edge, and said wheels carry sprocket-chains 26 which are connected by means of spaced apart transverse bars 25. The numeral 30' denotes spaced apart sprocket-wheels mounted on a trans- 40 verse rotary shaft 31, which carry the sprocket-chains 32, the latter connected by means of a slat-apron 37. The apron 37 is in alignment with the other conveyer, and located below its level, but adapted to receive 45 therefrom. The shafts 27 and 31 carry at their outer ends other sprocket-wheels 28 and 30 which are connected by the short inclined sprocket-chain 29. Said conveyer-chains are driven by the following 50 means.

The numeral 1 denotes fast-and-loose pulleys on a transverse rotary shaft 2 supported in fixed bearings on the frame-uprights 33 on each side of the intermediately- 55 located tank 22. On the end of said shaft

opposite to said pulleys is mounted a sprocket-wheel 43, and a sprocket-chain 39 connects it operatively with a sprocket-wheel 44 on said shaft 27, which drives said conveyers to the right.

On the shaft 2 is secured a pinion 3 which intermeshes with a gear-wheel 4 on the end of a transverse rotary shaft 5, the latter having its ends mounted in fixed bearings on said uprights 33. The pinion drives said shaft 5 at about one-half the speed of the shaft 2. Arms 6 have their ends pivotally mounted on the end portions of the rotary shaft 2, and their other extremities are furnished with bearings in which are mounted 60 the ends of a rotary shaft 7. On the ends of the shafts 5 and 7 are mounted the sprocket-wheels 42 and 41 respectively which are connected by a sprocket-chain 38, 65 which drives the shaft 7 in an opposite direction to the direction of rotation of the other shaft 5. Since the sprocket-wheels 42 and 41 are of the same diameter, the shaft 7 is driven at the same speed as the shaft 2, 70 which is but about twice the speed of the shaft 5.

I have adopted the following described means for moving the arms 6 up or down: A rack-segment 13 is pivoted on a pintle 11 in a bearing on the longitudinal beam 35, 75 the latter being supported by the uprights 33 and 34. A pinion 14 is pivoted on a stud-shaft 12 also mounted on said beam 35, and has a crank-handle 15, said pinion intermeshing with said rack-segment. Said 80 rack-segment has a radial slot 20, into which movably extends a stud 21 from one of the arms 6. When the crank 15 is rocked in either direction, by said intermediately-placed means said arms 6 are rocked up or 85 down, but the weight of the shaft 7 and other parts tends to keep the arms rocked downward to the limit.

Secured about the horizontal parallel 90 shafts 5 and 7 are a plurality of scraper-arms 16 and 17 respectively, which bear at their free extremities the scraper-blades 18 and 19 respectively. These scraper arms are of the same form and dimensions, and are made of some flexible material, such as rubber belting, or any other suitable material. The blades may be made of metal or other suitable material. The arms may be secured to cores or sleeves 36 secured to the 95 shafts, if desired.

In operation, the bodies of hogs in the scalding tank 22 are pushed along to the conveyer 26, whose transverse bars 25 contact the bodies one by one in succession, and 5 carry each upwardly under the shafts 5 and 7. The scraper-arms of said shafts rotate oppositely in the directions indicated by the arrows, and at the differential speeds mentioned, and thus the scraper-blades are 10 brought into rapid scraping engagement with the body lying thereunder and therebetween. As the scraper-arms are staggered with respect to each other on their shafts, no part of the surface of the body es- 15 capes the rubbing contact of the blades, which quickly denude it of bristles which drop through the open conveyer below. Since the shaft 7 rotates at double the speed of the shaft 5, the body is by the added op- 20 position of the arms thereon prevented from being carried off the conveyer, and is only rolled over and over. When properly denuded of bristles, the crank 15 may be lowered to raise the arms 6, and permit the 25 conveyer 26 to carry the body forward and deposit it upon the movable apron 37. It will be seen that since the lower part of the conveyer 26 is submerged in the scalding water in the tank, the hogs will float there- 30 on with little pushing, and that the action of the blades 16 will tend to splash water over the body all the while it is undergoing the process above outlined for denuding it of bristles, which facilitates the process, for the 35 ends of said scraper arms dip below the surface of the water in the tank.

Having described my invention, what I claim as new, and desire to secure by Letters Patent, is:

40 1. In combination a linearly movable member and flexible scrapers rotatably mounted thereabove and rotatable oppositely toward each other, one of said scrapers pivotally mounted to be swung out of the field of op- 45 eration.

2. In a device of the class described a longitudinally movable conveyer, oppositely rotatable shafts mounted thereabove, one of said shafts pivotally mounted to move rela- 50 tively the other, and flexible scrapers mounted on each shaft and adapted to move toward each other over a carcass brought between them and said conveyer.

3. In a hog scraping machine a support 55 for the carcasses, oppositely rotatable beater shafts in parallel relation rotated trans- versely across said support and spaced apart therefrom, one of said shafts being mounted in a fixed bearing and the other shaft being 60 mounted in bearings pivoted adjacent to said first shaft and movable to and from said support and said first shaft.

4. The combination with a movable sup- 65 porting and scraping mechanism for the car- cass, oppositely rotatable shafts rotated

thereabove, one shaft mounted in fixed bearings, a pivoted arm supporting the other shaft, means for moving said arm to and from said scraping mechanism, and a plurality of flexible scrapers movably mounted 70 upon said shafts.

5. In a device of the class described a conveyer, a pair of shafts, one pivoted to move eccentrically of the other, flexible scraper arms mounted on each shaft and scraper 75 blades secured on the extremity of each scraper arm.

6. The combination with a movable conveyer, of a plurality of flexible scraper mechanisms rotatably mounted thereabove, 80 one of said mechanisms movable about the other, said scraper mechanisms oppositely rotatable to impinge from either side upon a carcass held between them on said conveyer. 85

7. In a device of the class described oppositely rotatable shafts with differential speeds, one of said shafts pivotally mounted to move relative the other, flexible scrapers mounted on said shafts, and a movable sup- 90 porting and scraping element underneath said scrapers.

8. The combination of oppositely rotatable shafts, flexible scrapers mounted on each shaft in staggered relation, said shafts 95 being operable at differential speeds, one mounted in fixed bearings, the other movable at different distances therefrom.

9. The combination of oppositely rotatable horizontal shafts, a plurality of flexible 100 scraper arms secured on said shafts, an endless conveyer apron movable under said shafts, said shafts being rotated transversely above opposite ends of said apron, one of said shafts being mounted in fixed bearings, 105 and the other shaft being bodily movable to and from said conveyer apron and the other of said shafts.

10. The combination of an open tank, an inclined endless conveyer therein and pro- 110 jecting therefrom, a rotatable shaft trans- versely mounted in fixed bearings above the receiving end of said apron, and an oppo- sitely rotatable shaft mounted in bearings 115 transversely above the delivery end of said apron, the latter bearings and shaft being movable to and from said apron and the other shaft, and flexible scraper arms se- cured upon each of said shafts.

11. In a device of the class described a 120 casing, an endless conveyer, a tank in which said conveyer is partially inclined and sub- merged, oppositely rotatable shafts above and mounted transversely over the opposite ends of said conveyer, flexible scrapers 125 mounted upon each shaft, arms pivoted in the casing, the extremities thereof having bearings in which the ends of the other shaft are mounted, a racked segment having a radial slot pivoted to a supporting frame, 130

a supporting frame therefor, a pinion rotatably mounted on said frame and intermeshed with said racked segment and provided with a crank, one of said arms having 5 a stud movably projected into the slot in said racked segment.

12. The combination with an open tank, an endless conveyer chain connected by transverse slats mounted on sprocket wheels, 10 said chains lying in an inclined position partly within and partly without said tank, a rotatable shaft mounted in fixed bearings above the receiving end of the conveyer, and an oppositely rotatable shaft movable 15 at a differential speed and movably mounted above said delivery end of said conveyer and adapted to be moved to and from said conveyer, means for moving said second mentioned shaft to and fro, and a plurality 20 of flexible scraper arms secured about each shaft in staggered relation.

13. In a device of the class described a revolute supporting and scraping means for the carcass, beaters arranged thereabove, 25 and means throwing one of said beaters out of the field of action to permit discharge of the carcass.

14. In a hog scraping machine movable supporting and scraping means, a plurality 30 of rotatable scraping elements coacting therewith, and means moving one of said elements to permit discharge of the carcass therefrom.

15. In a device of the class described 35 scraping and supporting elements movable in a straight line, rotating, scraping and retaining elements coacting therewith to dehair a carcass, and means moving one of said elements relative the other to permit 40 discharge of the carcass therefrom.

16. In a device of the class described rotative yieldably mounted scrapers, a revolute supporting and scraping means for the carcass, means spraying the carcass with 45 water, and means moving certain of said scrapers to permit said carcass to be discharged.

17. In a device of the class described scrapers acting upwardly and downwardly 50 respectively on the carcass, and means moving said downwardly acting scrapers to permit the carcass to be discharged.

18. In a device of the class described supporting and scraping means for the carcass, 55 rotatable scrapers acting upwardly and

downwardly respectively on the carcass, and means moving one of said scraping means to permit the discharge of the carcass by others.

19. In a device of the class described a 60 plurality of rotative scraper elements, supporting and scraping elements revolving therebeneath, and pivoted means for throwing one of said elements out of action to permit discharge of the carcass.

20. In a device of the class described yieldable supporting and scraping mechanisms for the carcass, and yieldable rotatable scraping elements coacting therewith to dehair the carcass, one of said elements 70 pivoted to move relative the other to permit discharge of the carcass.

21. In a device of the class described rotatable scraping elements, supporting means for the carcass, and rack and pinion means 75 for moving one of said elements to permit discharge of the carcass.

22. In a device of the class described a partially submerged conveyer movable along a straight incline, beaters arranged to coact 80 therewith to spin and dehair the carcass, and means elevating one of said beaters to permit the discharge of the carcass when scraped.

23. In a hog-scraping device, the combination of a carrier to move the carcass, said carrier traveling in a fixed path, a rotary scraping-device supporting adjacent the carrier at a distance preventing normally a 90 carcass to pass it, and means to adjust the space between the two to permit a carcass to pass on with the carrier.

24. In a hog-scraping apparatus, the combination of a carrier adapted to support a carcass while resting lengthwise across the 95 same, said carrier traveling in a permanently fixed path, a rotary shaft provided above this carrier, means whereby this shaft is supported in a manner permitting adjustment of its position with reference to 100 the carrier, flexible scraper-arms mounted side by side upon the shaft, and scraping edges mounted on these arms.

Signed at Waterloo, Iowa, this 5th day of Oct., 1911.
